(21) Appl. No.: **29/240,650**

(57) **CLAIM**

(22) Filed: **Oct. 17, 2005**

The ornamental design for a container neck, as shown and described.

(51) LOC (8) Cl. **09-01**

DESCRIPTION

(52) U.S. Cl. **D9/434; D9/516**

The design is for a neck for a container. The neck has a plurality of threads and a lip.

(58) Field of Classification Search **D9/434,**

FIG. 1 is a perspective view of a container neck, embodying my new design;

D9/436, 449-458, 502, 516, 549, 550, 557,

FIG. 2 is a top view thereof; and,

D9/563, 571, 667, 686, 688-691; D7/509-511;

FIG. 3 is a side view thereof.

215/43-44, 382-384; 220/660, 669, 675

The broken line showing of the bottle is included for the purpose of illustrating portions of the bottle and forms no part of the claimed design.

See application file for complete search history.
